(57) **CLAIM**

The ornamental design for a handle, as shown and described.

DESCRIPTION

In a preferred embodiment, the nature of this product is as a handle, for example for grasping when opening a door or a drawer of a cooling unit, such as a compact refrigerator, freezer, beverage cooler, ice maker, combinations thereof and the like.

FIG. 1 is a left, top, front perspective view of a handle showing our new design; the bottom is not part of the claimed design, the handle is drawn broken away to show indeterminate length;

FIG. 2 is a front elevational view thereof;

FIG. 3 is a left side elevational view thereof, the right side elevational view thereof being a mirror image of the left side shown;

FIG. 4 is a top plan view thereof; and,

FIG. 5 is rear elevational view thereof.

The broken line representations in FIGS. 1–3 and 5 are for the purpose of illustration only, and form no part of the claimed design.
